UNITED STATES PATENT OFFICE.

EUGÈNE MARIE GEORGES LEPÈRE, OF PARIS, FRANCE, ASSIGNOR TO WEBB JAY, OF CHICAGO, ILLINOIS.

PRESSURE-FEED DEVICE FOR INTERNAL-COMBUSTION ENGINES.

1,329,781.

Specification of Letters Patent.

Patented Feb. 3, 1920.

Application filed December 23, 1918. Serial No. 268,042.

To all whom it may concern:

Be it known that I, EUGÈNE MARIE GEORGES LEPÈRE, a citizen of France, having residence at Paris, France, have invented 5 certain new and useful Improvements in Pressure-Feed Devices for Internal-Combustion Engines, of which the following is a specification, reference being had to the accompanying drawings, forming a part 10 thereof.

The purpose of this invention is to provide an improved construction for feeding liquid fuel to the carbureter of an internal combustion engine from a supply tank at a 15 lower level than the carbureter. It consists in the elements and features of construction shown and described, as indicated in the claims.

In the drawings:

20 Figure 1 is a vertical axial section of a structure embodying this invention, the same being shown in connection with the main fuel supply tank to which it is appended.

25 Fig. 2 is a top plan view of the same.

Fig. 3 is a detail section at the line, 3—3, on Fig. 2.

In the structure shown in the drawings, 1 represents the main fuel supply tank for an 30 internal combustion engine, not shown, but of which it may be understood that the carbureter is at a higher level than the said tank, 1. Appended to the tank, 1, in position to be supplied by gravity flow there- 35 from is an auxiliary receptacle comprising a chamber, 2, which directly receives the liquid fuel supply by gravity from the tank, 1, and a second chamber, 3, which receives the liquid fuel from the chamber, 2. It will 40 be understood that the tank, 1, has an at- mosphere inlet aperture at the top so that the liquid therein is exposed to atmospheric pressure and is free to be discharged, by gravity through any opening at the lower 45 part, and at such opening there is protruded a discharge nipple, 4, which extends up in the tank, 1, a short distance so as to leave a trap space at the bottom for accumulation of sediment and water. The pipe, 4, extends 50 down into the chamber, 2, of the auxiliary receptacle, and the discharge mouth therein is controlled by a check valve, 5, opening for discharge of the liquid into the chamber, 2, and seating in the opposite direction to 55 prevent return of the liquid or pressure

from the chamber, 2, into the tank, 1. The chamber, 2, discharges into the chamber, 3, through a fitting, 7, supplied with a check valve, 8, similar to the check valve, 5, and operating similarly to prevent return of the liquid from the chamber, 3, back into the chamber, 2. The chamber, 2, is constructed for being suspended inside of the chamber, 3, both said chambers having at their upper ends outwardly turned flanges, 2^a and 3^a, 60 respectively, lapping upon each other with opportunity for the interposition of packing to make the joints liquid-tight, said flanges serving as a means for securing both chambers together to the cap member, 10, which 65 is a casting having at its upper end a flange, 10^a, by means of which it may be secured to the bottom of the tank, 1. In the cap member, 10, there is provided an atmos- 70 phere inlet passage, 12, opening at the port, 12^a, into the top of the chamber, 2, the other end of said passage opening at the edge of the cap member, 10, and having preferably connected at that point a pipe, 13, which 75 extends upwardly to any desired height alongside the tank, 1, for safety against overflow or discharge of liquid through the atmosphere inlet in case of any derange- 80 ment of the apparatus which in its ordinary operation would prevent such an overflow. 85 In the cap member, 10, there is also provided a passage, 15, opening at the port, 16, through the cap into the top of the chamber, 2, said passage being extended for emerging 90 at the edge of the cap member, 10, and there 95 connects to a pipe, 17, leading from any source of super-atmospheric pressure, repre- 100 sented conventionally by the tank, 18, which may be understood to be a reservoir of compressed air interposed in a line leading to an air-compressing pump, not shown. In the passage, 15, there is interposed a Venturi throat piece, 20, from which at a point just beyond its constriction a relatively small restricted port, 21, leads off transversely 105 and registers with a port, 22, formed in the cap member, 10, opening into the annular space, 6, between the chambers, 2 and 3, and thereby effecting communication for super-atmospheric pressure to the chamber, 3.

Within the chamber, 2, there is mounted a valve mechanism for controlling the ports, 12^a and 16, through which respectively at- 110 mospheric pressure and super-atmospheric

pressure is admitted to the chamber, 2. The valve, 25, seating upwardly, controls the atmospheric inlet port, 12^a, and the valve, 26, seating downwardly, controls the pressure inlet port, 16. Both said valves are loosely connected with the lever, 27. Said lever, 27, and a second lever, 28, are both fulcrumed upon the same pivot, 29, carried by a lug, 30, which, projects downwardly from the cap member, 10, and the opposite extremities of said levers are connected by a spring, 32, stretched past the fulcrum of the two levers for producing a snap action in a manner which is familiar. A float, 31, in the chamber, 2, carried on an extended arm, 33, of the lever, 28, operates in a familiar manner to open the valve, 26, and close the valve, 25, when the float is lifted to a predetermined point by the rise of the liquid in the chamber, 2, and to reversely actuate said valves, closing the valve, 26, and opening the valve, 25, when by the fall of the liquid in the chamber the float descends to a predetermined point.

25 The operation of the structure above described is as follows:

The main tank, 1, being supplied with liquid and the auxiliary device being empty, the valve, 26, is closed and the valve, 25, 30 opened, the float being at the lowest position which it can reach in the chamber, 2; and liquid will flow from the tank, 1, into the chamber, 2, causing the same to be filled because the liquid cannot flow out of the chamber, 2, into the chamber, 3, on account of super-atmospheric pressure in the chamber, 3, holding the valve, 8, closed. When the chamber, 2, is filled with liquid to a predetermined point, lifting the float high enough 40 to cause the snap action of the valve-operated mechanism to occur, reversing the valves, seating the valve, 25, and opening the valve, 26, atmospheric escape being cut off and the super-atmospheric pressure admitted past the valve, 26, will cause the valve, 5, to be closed, preventing the further flow of liquid from the tank, 1, into the chamber, 2, and at the same time the pressure in the chamber, 2, with that being equalized previously existing in the chamber, 3, the liquid in the chamber, 2, will fall by gravity past the valve, 8, into the chamber, 3, until the liquid level in the chamber, 2, falling to a predetermined point, causes the float by its descent to operate the valve mechanism and actuate the valves for reversing them, and restoring the original conditions under which the liquid will cease to flow out of the chamber, 2, into the chamber, 3, and will 50 begin to flow again from the tank, 1, into the chamber, 2. The effect of opening the valve, 26, and closing the valve, 25, has been referred to as "equalizing" the pressure in the chamber, 2, which had previously existed in the chamber, 3; but it is the intention

of the construction described that the first effect, which is due to the employment of the Venturi throat-piece, 20, in the super-atmospheric air inlet passage, 15, shall be to withdraw fluid through the restricted port, 22, from the chamber, 3, simultaneously with the admission of super-atmospheric pressure to the chamber, 2. This happens because of the high velocity of the air current through the Venturi throat when the valve, 26, is first opened, and when the maximum difference exists between the pressure in the chamber, 2, and that derived from the source of super-atmospheric pressure. The need for thus reducing the pressure in the chamber, 3, while it is being increased in the chamber, 2, so that there shall not be exact equalization of pressure between the two chambers but at least some excess of pressure in the chamber, 2, over that in the chamber, 3, arises from the fact that the valve, 8, which controls the outflow of liquid from the chamber, 2, to the chamber, 3, is necessarily exposed to pressure over a larger area on the outer side than on the inner side, 90 and if the pressure in the two chambers were exactly equal, this would result in an excess of force tending to hold the valve seated, which would require a certain head of liquid in the chamber, 2, to overcome, in 95 order that the valve might open for discharge; and its opening would thereby be delayed, causing the operation of the apparatus to be sluggish. This is prevented by the expedient noted, consisting in the 100 employment of the Venturi throat-piece and restricted port for the withdrawal of super-atmospheric pressure from the chamber, 3. When the valve, 8, has opened and the flow of liquid has commenced from the chamber, 2, to the chamber, 3, or when without the opening of that valve the super-atmospheric pressure from the source is fully operative in the chamber, 2, the pressure in the two chambers would be equalized through the restricted port, 21, because at that stage there will be no appreciable current of air passing through the Venturi, and at least no velocity which would cause any reverse current through the port, 15, as the restricted port 110 would at all times afford sufficient access for super-atmospheric pressure to cause the discharge of the liquid from the chamber, 3, through the connection, 35, which leads to the carburetor at a higher level to which the 115 super-atmospheric pressure employed is at all times designed to be adequate to lift it, for maintaining the fuel supply to the carburetor float chamber, or for directly discharging in the mixing chamber in certain 120 forms of the carburetor.

I claim:

1. In a liquid supplying system, in combination with a source of liquid, a chamber to which the liquid is delivered from said 130

source; a non-return valve in the communication by which the liquid is delivered to said chamber; a source of super-atmospheric pressure; connections therefrom to said chamber; means operated by change of liquid level in the chamber for interrupting the access of the super-atmospheric pressure thereto; a second chamber into which the first chamber discharges, said second chamber having uninterrupted communication with the source of super-atmospheric pressure, and a non-return valve controlling the discharge communication from the first chamber into the second.

2. In the structure defined in claim 1, foregoing, means in the super-atmospheric pressure communication to the second chamber for relieving the pressure transmitted therethrough, when the super-atmospheric pressure communication of the first chamber is open.

3. In the structure defined in claim 1, foregoing, the super-atmospheric pressure communication of the second chamber consisting of a Venturi throat through which the pressure connection is made with the first chamber, said Venturi throat having a restricted port leading from a point inward from the constriction of said throat for communication with the second chamber; whereby the second chamber has restricted communication with the source of pressure and the pressure therein which is relieved by the free flow of the super-atmospheric pressure current through the Venturi throat when the pressure communication with the first chamber is open.

In testimony whereof I have hereunto set my hand at Chicago, Illinois, this 17th day of December, 1918.

EUGÈNE MARIE GEORGES LEPÈRE.
